UNITED STATES PATENT OFFICE.

FREDERICK G. WALKER, OF CLEVELAND, OHIO.

TROLLEY-WHEEL.

No. 884,546.

Specification of Letters Patent. Patented April 14, 1908.

Application filed May 18, 1906. Serial No. 317,524.

To all whom it may concern:

Be it known that I, FREDERICK G. WALKER, a citizen of the United States, resident of Cleveland, county of Cuyahoga, and State 5 of Ohio, have invented a new and useful Improvement in Trolley-Wheels, of which the following is a specification, the principle of the invention being herein explained and the best mode in which I have contemplated 10 applying that principle so as to distinguish it from other inventions.

My invention relates to means for movably contacting electrical conductors, and is especially adapted for utilization upon electrically-operated traction-cars, and is commonly known as the trolley-wheel.

It is the object of said invention to provide a never-slip and self-oiling trolley-wheel.

20 Said invention consists of means herein-after fully described and specifically set forth in the claims.

The annexed drawing and the following description set forth in detail certain mechanism embodying the invention, such disclosed means constituting but one of various mechanical forms in which the principle of the invention may be used.

In said annexed drawing: Figure 1 represents a side elevation of the upper end of a trolley-pole, and in connection therewith one form of my invention and a section of a trolley-wire. Fig. 2 represents a partial front elevation and a partial central vertical section of the features shown in Fig. 1. Figs. 3 and 4 represent central vertical sections respectively of two modified forms of my invention.

Referring particularly to Figs. 1 and 2: 40 The upper part of a trolley-pole is illustrated at A upon which is secured a support B which is fork-shaped, as shown, having an aperture b⁴ in each of its arms b, through each of which apertures is placed a contact-spring C secured at its bottom and exteriorly of the arms b of the support or trolley-harp B, as plainly shown in Fig. 2. At their lower extremities these contact-springs act as spring-bumpers. Secured at each of 50 its ends in hubs b' of the arms b by means of cotter-pins d in the slots b² is a journal-pin D. In the upper end of each of the arms b is formed a suitable aperture b³ through which the cotter-pins may be driven out.

55 The upper end of each of the springs C is

U-shaped, whereby it is adapted to engage with journal-pin D, as plainly shown in Fig. 1, and is furthermore adapted to be readily withdrawn for purposes of repair or replacement without having to dismount the wheel by drawing out the cotter-pin. Mounted upon said journal-pin D is a divided trolley-wheel comprising the two parts E E, which parts are complementary one to the other to form a complete wheel, and there being 60 formed between the same a pocket e⁸ adapted to receive the trolley-wire, said parts being independently rotatable upon the journal-pin D. Each of said parts E is provided with a bushing e' adapted to form a bearing 70 for the journal-pin D. Intermediately of the wheel-parts E and the upper end of the spring C are located washers c'. Within each wheel-part E is formed an annular oil-cell e that is formed with a continuous, or 75 substantially continuous internal opening e⁶ and with one or more external apertures adapted to be closed by means of plugs e², by the removal of which the cell may be replenished with oil. The bushings e' are a perfect 80 fit for the journal-pin D and can be readily replaced for repairs. Said bushings serve to hold the oil inside the wheel for self-oiling, and are provided with apertures e¹ adapted to communicate with aforesaid continuous 85 opening e⁶ of the corresponding wheel part to feed the oil to said pin.

As shown in Fig. 2, the trolley-wire lies in the central plane of the trolley-pole, which is the position it would assume when the car is 90 running upon a straight track, but when the car is rounding a curve the wire will climb into one of the positions illustrated in dotted lines in said Fig. 2, its point of contact with either of the wheel-parts E being substantially 95 in the central vertical plane of said wheel-part, whereby only one of said wheel-parts will be rotated, so that the rounding of the curve is not attended by any slippage between the wheel-part and the trolley-wire, 100 thereby very materially reducing the liability of a separation of the two and a consequent breakage of contact.

In the form of device shown in Fig. 3, a common bushing e³ is provided for the two 105 wheel-parts E' E', one of the wheel-parts, the right-hand one in the view shown, being loosely mounted upon the bushing e³, so as to turn relatively to the latter, and the left-hand one being fitted tightly upon said bush- 110

ing; and in the form of device shown in Fig. 4 one bushing e^1 is provided for the wheel-part E^2 , and also a single oil-cell e . The path of the current is through the trolley-wire to the 5 wheel-parts E , bushings e' , washers c' , spring-contacts C , support B , to the trolley-pole A .

The wheel-parts E and the bushings e' are 10 preferably made of a composition metal which is very hard and a good conducting medium, while the journal-pin D is made of machinery steel and case hardened. The washers c' are preferably made of pressed steel, the contact-springs C of a composition 15 stamp sheet metal, and the fork or support B of malleable iron or a composition metal. As shown, the two faced surfaces e^2 of the wheel-parts E are arranged parallel with one another and perpendicular to the journal- 20 pin D . Obviously various changes in these particulars can be made if found for any reason desirable, which changes it has not been thought necessary to illustrate as they do not relate to the subject-matter of the present 25 invention.

Having thus described my invention in detail, that which I particularly point out and distinctly claim, is:

1. In a trolley wheel, the combination of a 30 trolley harp; a pin mounted in said harp; a bushing fitted around said pin; a wheel member mounted upon said bushing, said wheel member being formed with an annular oil-cell, having a continuous internal opening 35 and an external opening for receiving an oil supply, and said bushing being provided with apertures adapted to communicate with said oil-cell opening; a washer of larger diameter than said bushing at one end of the same; and a spring bearing inwardly against 40 said washer, the upper end of said contact spring being U-shaped whereby the same may be removed without dismounting the wheel, substantially as described.
2. In a trolley-wheel, the combination of a 45 trolley harp; a pin secured in said harp; two contiguous bushings fitted around said pin; a washer of larger diameter than said bushings at the respective outer ends of the same; 50 springs respectively bearing inwardly against said washers; and two complementary wheel parts corresponding with said bushings, each of said wheel parts being formed with an annular oil cell having a substantially continuous internal opening, and each of said bushings being provided with apertures adapted to register with such continuous opening of the correspond- 55 ing wheel part.

to register with such continuous opening of the corresponding wheel part.

3. In a trolley-wheel, the combination of a support; a pin secured therein; two independent complementary wheel-parts, mounted upon said pin and arranged to form a pocket for the trolley-wire; bushings within said wheel-parts forming a bearing for said pin, 60 said wheel-parts being formed with an inclosed oil-cell; and contact-springs engaging with said bushings, respectively, and secured to said support.

4. In a trolley wheel, the combination of a trolley-harp having an apertured arm; a pin secured in said trolley-harp; a bushing fitted around said pin; a wheel member mounted upon said bushing, said wheel member being formed with an annular oil-cell having a continuous internal opening and an external 75 opening for receiving an oil supply, and said bushing being provided with apertures adapted to communicate with said oil-cell opening; a washer of larger diameter than said bushing at one end of the same; and a contact 80 spring attached at its lower extremity exteriorly of said apertured arm and extending upwardly through the aperture in the same to laterally engage said washer, the upper end of said contact spring being U-shaped 85 whereby the same may be removed without dismounting the wheel, substantially as described.

5. In a trolley-wheel, the combination of a trolley harp having apertured arms; a pin secured in said trolley harp; two contiguous bushings fitted around said pin; a washer of larger diameter than said bushings at the respective outer ends of the same; two contact springs attached at their lower extremities exteriorly of said arms, respectively, and extending upwardly through the apertures in the same to laterally engage said washers; and two complementary wheel parts corresponding with said bushings, each of said 90 wheel parts being formed with an annular oil cell having a substantially continuous internal opening, and each of said bushings being provided with apertures adapted to register with such continuous opening of the correspond- 95 ing wheel part.

Signed by me, this 23rd day of April 1906.

FREDERICK G. WALKER.
